UNITED STATES PATENT OFFICE.

EDWARD S. SAVAGE, OF ROCHESTER, NEW YORK.

MICROMETER-CALIPER.

1,107,203.

Specification of Letters Patent. Patented Aug. 11, 1914.

Application filed December 20, 1913. Serial No. 807,959.

To all whom it may concern:

Be it known that I, EDWARD S. SAVAGE, a citizen of the United States, and resident of Rochester, in the county of Monroe and 5 State of New York, have invented certain new and useful Improvements in Micrometer-Calipers, of which the following is a specification.

This invention relates to micrometer-10 calipers or measuring-tools of the type in which a screw-threaded spindle is rotated by means of a manually-operable handle or barrel, the position of the spindle or screw being indicated by means of graduations or 15 other indicating devices coöperating with the barrel.

In a micrometer-caliper invented by me and disclosed in a pending application, for Letters Patent of the United States, filed 20 May 19, 1913, Serial No. 768,566, I employ a construction and arrangement of parts by 25 which longitudinal movement of the barrel is avoided, the barrel being connected with the micrometer-screw by sliding connections which compel the screw to rotate with the barrel while permitting relative longitudinal movement.

One object of the present invention is to provide a micrometer-caliper, so constructed, 30 with improved means for adjusting the caliper to cause it to indicate correctly the position of the screw, whereby I avoid the necessity of using an adjustable anvil in the usual manner. To this end I interpose, between 35 the micrometer-screw and the barrel, connecting-devices which normally cause the screw to rotate in unison with the barrel, but which may be loosened so as to permit relative rotation of these parts, thus permitting 40 the barrel and the indicating-devices coöperating therewith to be adjusted to conform accurately to any definite position in which the screw is temporarily held during the adjusting operation.

45 Another object of the invention is to provide a micrometer-caliper with a simple and effective device for locking it in any position in which it may be set. This novel locking-device is applicable to micrometer-calipers of 50 various forms, but may be most conveniently applied to a caliper of the particular type in question, since it is adapted conveniently to coöperate with a barrel which does not

move longitudinally. The locking-device comprises an annular member, rotatable 55 about the axis of the micrometer-screw and the barrel, and provided with one or more inner beveled surfaces, together with a member adapted to simultaneously engage such inclined surface and the outer surface of the 60 barrel or other rotatable part of the caliper, so that by forcible rotation of the annular member the clamping-member may be forced into clamping engagement with such rotatable member, to lock it frictionally against 65 rotation.

In the accompanying drawings:—Figure 1 is a side-elevation, partly in vertical section, of a portion of a micrometer-caliper embodying the present invention; and Figs. 70 2 and 3 are vertical sections on the lines 2—2 and 3—3, respectively, in Fig. 1, looking from left to right.

The invention is illustrated as embodied in a micrometer-caliper of a general form 75 which is familiar, this caliper having, as usual, a yoke 4, of which one end only is illustrated, and a screw-threaded spindle or micrometer-screw 5 which is movable within the usual screw-threaded sleeve 6 fixed to the 80 yoke. The screw 5 is turned, in the usual manner, by the rotation of a barrel 7 coaxial with the screw.

As in the device of my said application, the barrel 7 is not fixed to the longitudinally 85 movable screw 5, but is made hollow, so that the screw may move longitudinally within it. A longitudinal slot or key-way 8, in the barrel, receives a key 9 fixed to the end of the screw, however, so that when the barrel is 90 rotated the screw is caused to rotate with it, and thus to move lengthwise through the sleeve 6 in the operation of setting the caliper.

Any convenient means may be employed 95 for preventing longitudinal movement of the barrel 7, but in the illustrated caliper this is accomplished by connecting the barrel with direct-reading indicating-mechanism comprising a series of graduated rings. One of 100 these rings, designated by the reference-number 10, is fixed to the barrel and rotates within a casing 11, which has a reduced extension 12 in which the barrel is journaled; and the ring 10, by its engagement with the 105 casing and with other parts of the indicat-

ing-mechanism, prevents endwise movement of the barrel, while leaving it free to rotate. This indicating-mechanism may be of any ordinary or suitable form, and accordingly 5 it is not particularly described or illustrated herein.

The novel construction, constituting a feature of the present invention, by which I provide for the adjustment of the caliper, 10 resides in an arrangement by which the key 9 is secured to the screw 5. This key is integral with a head 13 having a cylindrical shank 14 which fits in a recess in the end of the screw. A binding-screw 15, threaded 15 into the head 13, is provided with a conical extremity coöperating with a conical surface within the cleft extremity of the shank 14. Accordingly, when this screw is driven inwardly it expands the shank, so as to bind it 20 tightly to the screw and thus lock the key and the screw together. When adjustment of the caliper is necessary, however, the screw 15 is loosened, and the head and the key may then turn relatively to the micrometer-screw 5. To adjust the caliper it is then 25 necessary only to set the screw against a gage of predetermined diameter, or against the anvil of the caliper, and then hold it in this position while turning the barrel 7 until the indicating-mechanism shows the 30 proper dimension. The screw 15 is then tightened to set the parts in adjusted position. To afford access, when necessary, to the screw 15, while closing the barrel normally 35 against the admission of foreign substances, a removable plug 16 is screwed into the end of the barrel. Accidental end-wise movement of the shank 14 with respect to the screw is prevented by a pin 20 fixed in the screw and engaging an annular groove in the shank.

The locking-device, constituting the second feature of the invention, comprises a ring 18 which is mounted rotatably upon the 40 extension 12 of the casing. This ring is provided with a continuous recess in its inner surface, and this recess, as shown particularly in Fig. 2, comprises two opposite portions of gradually increasing depth, the bottoms of these portions being thus formed by inclined surfaces. Coöperating with the ring 18 are two clamping-members 17, in the form of short cylindrical pins, which are mounted to slide radially in perforations in 45 the extension 12. These pins extend into position to engage simultaneously the outer surface of the barrel 7, and the inclined inner surfaces of the ring. When the ring is in the normal position shown in Fig. 2 the pins coincide with the portions of greatest depth in the recesses, and are not subjected to any endwise pressure, so that the barrel 50 may be rotated freely. But when the ring is turned in a clockwise direction from the position of Fig. 2, the inclined surfaces force

the clamping-members with increasing pressure against the surface of the barrel, thus locking it frictionally against rotation.

In assembling the caliper the locking-ring is slipped into place upon the casing, and the pins are then placed as shown in Fig. 2. The barrel is then introduced, and thereafter the ring is retained in place by its engagement with the pins, and cannot become disengaged therefrom so long as the barrel remains in position. Accordingly, my improved lock is very simple in construction, while its parts are effectively held in their operative relation.

I claim:—

1. In a micrometer-caliper, the combination of a micrometer-screw, a manually-rotatable barrel, means for preventing longitudinal movement of the barrel, and longitudinal sliding connections between the barrel and the screw to cause the screw to rotate with the barrel, said connections comprising members relatively rotatable to permit relative adjustment of the barrel and the screw, and means normally retaining said members against such relative rotation.

2. In a micrometer-caliper, the combination of a micrometer-screw, a manually-rotatable barrel provided with a longitudinal key-way, means for preventing longitudinal movement of the barrel, a key coöperating with said key-way and rotatable relatively to the screw, and means normally fixing the key to the screw against such relative rotation, said means being adapted to be loosened to permit such relative rotation for the purpose of adjustment.

3. In a micrometer-caliper, the combination of a micrometer-screw, a manually-rotatable barrel provided with a longitudinal key-way and with a removable end-closure, a key coöperating with said key-way and rotatably connected with the micrometer-screw, and means, including a binding-screw, for fixing the key normally against rotation with respect to the micrometer-screw, said binding-screw being accessible through the end of the barrel when said end-closure is removed.

4. In a micrometer-caliper, the combination, with a fixed part and a part rotatable with the micrometer-screw, of a locking-device, for locking said parts together comprising a clamping-member non-rotatably connected with said fixed part but movable radially into clamping-engagement with said rotatable part, and a rotatable annular member having an inclined surface coöperating with the clamping-member and adapted to force it inwardly upon a partial rotation of the annular member.

5. In a micrometer-caliper, the combination, with a part rotatable with the micrometer-screw, and a fixed annular member surrounding said part and provided with radial

perforations, of members mounted slidingly in said perforations and adapted to engage the outer surface of said rotatable part, and a rotatable annular member surrounding the fixed annular member and having a recess, in its inner surface, coöoperating with the outer ends of the sliding-members, and provided with inclined surfaces adapted to force

the sliding members inwardly into locking engagement with the rotatable part upon a 10 partial rotation of the rotatable annular member.
